WILLIAM BRADY, OF OSSINING, NEW YORK.

APPARATUS FOR CLEANING WINDOWS.

Application filed December 11, 1925. Serial No. 74,792.

This invention relates to improvements in window wipers for locomotives, automobiles, and the like, and has for its object to provide a combined scraper and wiper which is automatically actuated by mechanism operated by a relatively small amount of power or fluid pressure.

Another object of this invention is to provide a combined scraper and wiper, which will be oscillated and caused to clean a substantially square surface of the window or glass.

Another object is to provide a device having a scraper and cleaning attachment which presents the smallest possible obstruction to the vision of the operator.

Another object is to provide a device which is simple in construction and reliable in operation.

Another object is to provide certain improvements in the form, construction and arrangement of the parts whereby the above named and other objects may be effectively attained.

A practical embodiment of my invention is represented in the accompanying drawings, in which

Fig. 1 represents a plan view of my improved device attached to a portion of a window frame.

Fig. 2 represents a front elevation of the same, certain of the parts being shown in section.

Fig. 3 represents an end elevation of the same.

Fig. 4 represents a vertical section taken in the plane of the line IV-IV of Fig. 2, looking in the direction of the arrows.

Fig. 5 represents a vertical section taken in the plane of the line V-V of Fig. 2, looking in the direction of the arrows.

Fig. 6 represents a vertical section taken in the plane of the line VI-VI of Fig. 2, looking in the direction of the arrows.

Fig. 7 represents a detail horizontal section, on an enlarged scale, taken in the plane of the line VII-VII of Fig. 3.

Fig. 8 represents a detail front elevation, partly in section, on the same scale as Figs 1 to 6 inclusive, showing the parts in another position from that shown in the previous figures, and

Fig. 9 represents a horizontal section on an enlarged scale, of a modified form of scraper and wiper.

The device as a whole is mounted upon a plate denoted by 1 which is secured to the side rails 2, 3 of the window frame, in the present instance, by means of screws 4-4, 5-5. The plate 1 is formed with an upwardly extending portion 6 which has a tubular bearing 7 mounted in a hole 8 in the upper rail 9 of the window frame. A sleeve 10 is journaled in the tubular bearing 7, one end of which is arranged to receive an arm 11, which is secured thereto by means of a nut 12 which engages a threaded end 13 of the sleeve. A shaft 14 is mounted to slide longitudinally in the sleeve 10 and held against rotation by means of a key 15 70 coacting with the sleeve and shaft. The outer end of the shaft 14 is provided with an enlarged end 16 arranged to receive a depending arm 17 secured thereto by a set screw 18. 75

A wiper 19 is mounted in a U-shaped carrier 20 which is arranged to oscillate on a bolt 21 fixed in the end of the arm 17. The wiper comprises a member 22 having a longitudinal channel 23, in which is secured a 80 flexible contact member 24, of rubber or other suitable material, which may be caused to press against the glass 25 of the window. Upon opposite sides of the member 22 I secure metal scrapers 26, 27 having outwardly 85 turned sharp edges 28, 29 respectively. The member 22 is fixed in the carrier 20 by means of a bolt 30 and nut 31, and permitted to vibrate slightly on the bolt, so that the flexible member 24 will assume a position substantially parallel with the glass 90 when in contact therewith, thus tending to equalize the pressure of the member on the glass throughout its length. The wiper and carrier is limited in its oscillatory movement on the arm 17 by means of a bell crank lever 32 pivoted at 33 on the arm 17, of which one branch 34 of the lever 32 has a pin 35 arranged to be engaged by the upper end of the wiper, while the branch 36 has 95 a pin 37 which projects into the path of the upper end of the wiper in its movement in the other direction.

This wiper 19 is so mounted in the U-shaped carrier 20 that the distance from the bolt 30 to the bottom of the wiper is greater than the distance from the bolt to the top. The wiper being so hung will function so as to normally overbalance the wiper on the pivot bolt 21, thereby creating a drag 110

or friction on the lower end as the arm 17 is oscillated.

The flexible element and scrapers are held 5 yieldingly in contact with the glass 25 of the window by means of springs 38, 38* disposed on the shaft 14. The spring 38 is interposed between the nut 12 and a thumb screw 39 which has a threaded engagement with the end of the shaft 14, while 10 the spring 38* is located between the sleeve 10 and the enlarged end 16 of the shaft 14.

The mechanism for rocking the sleeve 10 and shaft 14 together with the arms 11 and 15 17 comprises a cylinder 40 having a piston 41 arranged to reciprocate therein, which piston is provided with a rod 42 which is 20 slidable in a gland 43 of the head 44 of the cylinder 40. A stud 45 is fixed to the piston rod 42 and arranged to engage a slot 46 in the end of the arm 11. The outer end 25 of the piston rod 42 is slidable in a block 47, carried by the plate 1, and held against rotation by means of a key 48 fast to the block 47 and arranged to extend into a 30 groove 49 in the piston rod. The cylinder 40 is secured to the plate 1 at 50, and is closed at its end by a head 51.

A valve chamber 52 is disposed adjacent 35 the cylinder 40 and provided with a reciprocating valve rod 53 which is slidable in a gland 54 of the head 44 and provided with piston valves 55, 56 which reciprocate in the valve chamber 52. The outer end 40 of the valve rod 53 is arranged to reciprocate 45 in a block 57 carried by the plate 1 and held against rotation by means of a key 58 secured to the block 57 and a groove 58* in the valve rod. The valve chamber also has 50 exhaust ports 59, 60 and an inlet 61. The 55 inlet 61 is located in position in the valve chamber so as to admit fluid pressure between the piston valves 55, 56 at all times.

Passages 62, 63 are located in the wall 45 between the cylinder 40 and valve chamber 52 and are arranged to open communication between the valve chamber and cylinder and also exhaust the fluid pressure from the cylinder through the exhaust ports 59, 60. The piston valves 55, 56 on the valve rod 53 are arranged to control the opening and closing of the passages 62, 63 respectively to admit or exhaust fluid pressure to and from the cylinder 40. The movement of the valve rod 53 is controlled and operated 55 by means of a finger 64, which is secured to, and depends from the piston rod 42. This finger 64 moves with the piston rod 42 and is arranged to engage studs 65, 66 extending laterally from the valve rod 53. 60 The valve rod is held in position by means of a spring actuated plunger 67, the upper end of which is provided with a tooth 68 arranged to enter notches 69, 70 in a rack 71 secured to the valve rod by means of the 65 stud 66. The plunger is mounted in a

bracket 72 carried by the valve chamber 52 and the tooth 68 is yieldingly held against one or the other of the notches 69, 70 by means of a spring 73, the tension of which may be regulated by a nut 74 having a threaded engagement with the housing 75 of the plunger.

In Fig. 9 I have shown a modified form of scrapers and wiper mounted in a U-shaped carrier 76 and carried by a bolt 77 in the end of an oscillating arm 78. This wiper comprises a member 79, having a longitudinal channel 80, the outer edges of which are turned outwardly and provided with sharp edges 81, 82. A flexible contact member 83 of rubber or other similar material is secured in the longitudinal channel and may be caused to press against the glass of the window in the manner shown and described in the previous figures.

The operation of the device is as follows:—

When the piston valves 55, 56 are in the position shown in Fig. 2, the passage 62 is in open communication with the chamber 90 at the left of the piston 41, while the passage 63 opens a free passage with the chamber at the right of the piston 41 to the atmosphere through the exhaust port 60. In the position of the piston valve above named 95 the fluid pressure being applied to the inlet pipe 61 will enter the valve chamber 52, thence pass through the passage 62 into the cylinder 40 and exert its force upon the piston 41 which will be moved to the right. 100 This movement of the piston 41 actuates the rod 42 and through the stud 45 fast on the rod, being in engagement with the slot 46 in the arm 11, the shaft 14 will be rocked, which movement of the shaft 14 oscillates 105 the arm 17 and hence the scrapers and wiper.

The finger 64 being fast on the rod 42 will also be moved so as to be brought into contact with the stud 66 on the valve rod 53 110 which will be moved until the piston valve 55 closes the passage 62, thereby cutting off the fluid pressure to the cylinder 40 there-through. As the valve rod 53 is moved by the finger 64, the rack 71, which is fast on the rod 53 will be caused to depress the plunger 67 and force its tooth 68 out of the notch 69 and into engagement with the notch 70. When the bevelled face of the tooth 68 engages the notch 70, the tooth will ride 115 upwardly on the side of the notch and, by reason of the spring 73 having an upward stress, the tooth will push the rack 71 and the rod 53 to the right until the tooth completely registers with the notch, as shown 120 in Fig. 8, in which position the valve rod 53 will have moved the piston valve 56 and opened the passage 63 to the valve chamber 52, whereupon the fluid pressure will enter 125 the cylinder 40 at the right of the piston 130

41 and the motive force exerted to move the piston and rod to the left. As the piston valve 56 was moved to open the passage 63 to the valve chamber 52, the piston valve 55 simultaneously uncovered the passage 62 and opened the chamber at the left of the piston 42 to external atmosphere through the exhaust port 59. By the movement of the piston 41 and rod 42, the finger 64 will 10 be moved into engagement with the stud 65 on the valve rod 53, which will be carried along until the piston valve 56 closes the passage 63, at which position the rack 71 will have depressed the plunger 67 and 15 caused the tooth 68 to enter the notch 69 and reset the piston valves 55, 56 to the position shown in Fig. 2, when the cycle of operation will be repeated.

With the movement of the rod 42, the 20 stud 45 actuated the arm 11 which in turn rocked the shaft 14 with its arm 17 and hence the scrapers and wiper on the surface of the window glass.

In order that the wiper may be caused to 25 clean a substantially rectangular surface of the window glass, the wiper while being oscillated with the arm 17 is also mounted to oscillate on the bolt 21 journaled in the arm 17. As the arm 17 is moved to and fro, the 30 wiper will be caused to assume an approximate vertical position. This position is maintained throughout the movement of the ram 17 by one or the other of the pins 35, 37 on the branches 34, 36 of the bell crank 35 lever 32. For instance, if the wiper, as shown 35 in Fig. 2, is to be moved to the right, the pin 35 on the branch 34 will engage the upper end of the wiper and maintain the same in an upright position and against movement 40 on the bolt 21. If the wiper, as shown in Fig. 8, is to be moved to the left, the pin 37 on the branch 36 will contact with the upper end of the wiper and hold the same substantially in a vertical position throughout 45 its movement to the left. The rocking movement of the bell crank lever 32 on its pivot 33 to bring the pins into engagement with the wiper, is automatically controlled by the upper end of the wiper, which is 50 caused to swing on its bolt at each change in the direction of travel of the arm 17.

While I have shown and described the wiper arranged to be oscillated on the arm 55 17, I also wish it understood that the wiper may, if desired, be held rigid on the arm 17 by locking the carrier securely to the arm 17 through the bolt and nut 21 in which position the wiper will then be caused to clean 60 an arcuate surface of the window glass.

It will also be seen that the sharp edges of the scrapers will function to remove any foreign matter, such as ice, sleet and snow, from the window glass, while the flexible contact member, interposed between the

scrapers, will clean the surface of the window glass previously engaged by the scrapers.

It will also be understood that by unscrewing the thumb nut 39 on the shaft 14, the tension of the springs 38, 38* may be relieved and the flexible element alone caused to engage the window glass.

It is obvious that various changes may be resorted to in the form, construction and arrangement of the several parts without departing from the spirit and scope of my invention; and hence, I do not intend to be limited to the details herein shown and described except as they may be included in the claims.

What I claim is:

1. An apparatus for cleaning windows comprising, a plate adapted to be fixed to a window frame and provided with a tubular bearing, a sleeve journaled in said bearing, an arm fixed on said sleeve, a shaft mounted to rotate with the sleeve, a wiper arm carried by said shaft, means on said wiper arm pivotally supporting a cleaning element, a device pivoted on the wiper arm and having abutments arranged to be engaged by the upper end of the cleaning element to arrest and limit its movement in opposite directions, and mechanism coacting with the arm on the sleeve for oscillating the shaft and wiper arm.

2. An apparatus for cleaning windows comprising, a plate adapted to be fixed to a window frame and provided with a tubular bearing, a sleeve journaled in said bearing, an arm fixed on said sleeve, a shaft mounted to rotate with the sleeve, a wiper arm carried by the shaft, means on said wiper arm pivotally supporting a cleaning element, a bell crank lever pivoted on the wiper arm and having abutments arranged to be engaged by the upper end of the cleaning element to arrest and limit its movement in opposite directions, and mechanism coacting with the arm on the sleeve for oscillating the shaft and wiper arm.

3. An apparatus for cleaning windows comprising, an oscillatable wiper arm, a cleaning element carried thereby, said element including a longitudinal holder attached to said arm, a resilient contact member secured to said holder, said member being formed of a flat strip of flexible material folded to form a hollow portion adjacent the contact surface, and scrapers disposed on opposite sides of said member to engage the window glass when the member is compressed.

4. An apparatus for cleaning windows comprising, an oscillatable wiper arm, a cleaning element carried thereby, said element including a carrier pivoted to said wiper arm, a longitudinal holder mounted to oscillate laterally in said carrier, a resil-

ient contact member secured to said holder, said member being formed of a flat strip of flexible material folded to form a hollow portion adjacent the contact surface, and 5 scrapers disposed on opposite sides of said member to engage the window glass when the member is compressed.

5. An apparatus for cleaning windows comprising, a plate adapted to be fixed to 10 a window frame and provided with a tubular bearing, a sleeve journaled in said bearing, an arm fixed on said sleeve, a shaft mounted to rotate with the sleeve, a wiper arm rotatable with said shaft, means on said 15 wiper arm supporting a cleaning element, said cleaning element including a resilient contact member, said member being formed of a flat strip of flexible material folded to form a hollow portion adjacent the contact 20 surface, scrapers disposed on opposite sides of said member and arranged to be brought into engagement with the window glass, yielding means on the shaft interposed between the sleeve and wiper arm for normally 25 holding the scrapers out of engagement with the window glass, and mechanism coacting with the arm on the sleeve for oscillating the shaft and wiper arm.

6. An apparatus for cleaning windows

comprising, a plate adapted to be fixed to a window frame and provided with a tubular bearing, a sleeve journaled in said bearing, an arm fixed on said sleeve, a shaft mounted to rotate with the sleeve, a wiper arm fixed to said shaft, means on said wiper 35 arm supporting a cleaning element, said cleaning element including a resilient contact member, said member being formed of a flat strip of flexible material folded to form a hollow portion adjacent the contact 40 surface, scrapers disposed on opposite sides of said member and arranged to be brought into engagement with the window glass, yielding means on the shaft interposed between the sleeve and wiper arm for normally 45 holding the scrapers out of engagement with the window glass, means for moving the shaft longitudinally in the sleeve for compressing the resilient member and bringing 50 the scrapers into contact with the window glass, and mechanism coacting with the arm on the sleeve for oscillating the shaft and wiper arm.

In testimony, that I claim the foregoing as my invention, I have signed my name 55 this 8th day of December, 1925.

LOUIS HACHENBERG.
